UNITED STATES PATENT OFFICE.

HERMAN KADOW, OF NEWARK, NEW JERSEY.

CATCH FOR BAGS.

SPECIFICATION forming part of Letters Patent No. 394,861, dated December 18, 1888.

Application filed February 28, 1888. Serial No. 265,633. (No model.)

To all whom it may concern:

Be it known that I, HERMAN KADOW, a citizen of the United States, residing at the city of Newark, Essex county, New Jersey, have 5 invented certain new and useful Improvements in Satchel or Bag Catches; and I do hereby declare the following to be a full, clear, and exact description of the invention, reference being had to the accompanying drawings, which form part of this specification.

My invention relates to satchel-catches, and has for its object the provision of a catch of novel construction, neat, and compact, and which will lock or catch automatically when 15 the satchel is closed and will hold the same firmly in its closed position.

My invention consists in the novel construction, combinations, and arrangement of parts hereinafter described, and specifically 20 claimed.

Referring to the accompanying drawings, Figure 1 is a perspective view of the frame of a bag or satchel with my improvement applied thereto. Fig. 2 is a vertical longitudinal sectional view of the catch apart from the bag. Fig. 3 is a perspective view of the casing with the movable parts removed, and Fig. 25 4 is a plan view of a portion of the catch.

The catch-easing consists of a rectangular 30 box of metal, C, having a cavity on top for the reception of a pivotal lever, D, and provided with depending ears c c, which pass through holes in the bag-frame A and are bent around inside the same. The casing C 35 has on each side of the cavity in which the lever D lies a notch, j, which serves to receive pintles i i on each side of said lever. Upon the bottom of lever D, and in line with pintles i i, is a lug, h, which bears against a 40 spring, E, fastened within casing C. The lug h is curved on one side and straight on the other, the intersection of the curved and straight sides forming a corner, so that when the lever is raised until the corner of the lug 45 is in contact with the spring the lever will remain in such position until forcibly depressed. The lever D is also formed with two depending lugs, d e, the edges of which are oppositely beveled, as shown, and the said lugs 50 project through coinciding holes in the spring E and frame-piece A. The lug d is somewhat longer than the lug e, and is beveled in such direction that the contact of the hasp, with

which it engages when the bag is closed, will elevate the lever sufficiently to allow the hasp 55 to pass under the end of the lug.

B designates a second frame-piece pivoted to the piece A at a b and carrying a hasp, B', in which there are two holes, f g, into which alternately enter the lugs d e of the lever D 60 as the catch is operated.

The catch constructed as above described operates in the following manner: When the satchel is closed, the catch-lever D occupies the position in which it is shown in Fig. 2, 65 the lug d projecting into the hole f of the hasp when the lever is in this position, and the lug e being above the hole g of the hasp, but not projecting into or through the same. To open the satchel, the lever D is raised at the 70 end nearest the lug d and turns upon its pintles i i until the corner of lug h is in contact with spring E. The lug e is by this movement of the lever projected through the hole g in the hasp B', and upon opening the bag 75 by spreading apart the frame members A B the hasp, bearing against the beveled edge of the lug e, forces the lever back into its original position. Upon bringing the pieces A B together in closing the bag, the hasp, contacting with the beveled edge of lug d, raises the lever a sufficient distance to allow the said lug to pass into hole g, and the spring E forces the lever home.

What I claim as new is—

1. In the clasp herein described for bags or satchels, the combination, with a spring and with the lever eccentrically pivoted upon one member of the frame of the bag and provided with depending oppositely-beveled lugs, of a 90 hasp secured to the other member of said frame and having holes with which said depending lugs engage alternately as the bag is opened and closed, substantially as described.

2. A clasp or fastening for satchels or bags, 95 consisting of a box, C, a pivoted lever, D, having downwardly-extended tongues d e, a spring, E, and a hasp, F, having openings f g, as set forth.

In testimony that I claim the foregoing I have hereunto set my hand this 17th day of January, 1888.

HERMAN KADOW.
